RATCHET MECHANISM FOR WRENCHES,
SCREW DRIVERS, AND THE LIKE

Roe V. Browning and Cecil F. Badgley, Bozeman, Mont.; said Badgley assignor of twenty-five per cent to Ottley R. Tschache and twenty-five per cent to J. W. Tschache, both of Bozeman, Mont.

Application September 9, 1949, Serial No. 114,850

7 Claims. (Cl. 192—48)

1

Our invention relates to ratchet mechanism for wrenches, screw drivers and the like.

A primary object of our invention is to provide mechanism of the above mentioned type which is smooth operating, without the usual clicking noise, and extremely simple, compact and sturdy in construction.

A further object is to provide ratchet mechanism which is positive in its gripping action upon the tool to be turned, and which will release the tool without effort, regardless of the force previously applied for turning a screw or the like.

A further object is to provide mechanism of the above mentioned type which is free from levers, pins, wheels and the like, usually needed to control the ratchet reverse.

A still further object of our invention is to provide ratchet mechanism adjustable to right and left hand turning positions and to a position where the mechanism is positively locked to the tool for turning therewith.

Other objects and advantages of our invention will be apparent during the course of the following description:

In the accompanying drawings, forming a part of this application, and in which like numerals are employed to designate like parts throughout the same,

Figure 1 is a central vertical longitudinal section through ratchet mechanism embodying our invention, part broken away,

Figure 2 is a similar section illustrating a modification of the invention,

Figure 3 is a horizontal transverse section taken on line 3—3 of Figure 1,

Figure 4 is a similar section taken on line 4—4 of Figure 1,

Figure 5 is a similar section taken on line 5—5 of Figure 1,

Figure 6 is a similar section taken on line 6—6 of Figure 1,

Figure 7 is a central vertical longitudinal section through ratchet mechanism embodying a further modification of the invention,

Figure 8 is a similar section showing a still further modification of the invention,

Figure 9 is a horizontal transverse section taken on line 9—9 of Figure 7,

Figure 10 is a similar section taken on line 10—10 of Figure 7,

Figure 11 is a similar section taken on line 11—11 of Figure 8,

Figure 12 is a similar section taken on line 12—12 of Figure 7,

Figure 13 is a similar section taken on line 13—13 of Figure 7, and,

2

Figure 14 is an end elevation of the mechanism shown in Figure 7.

In the drawings, where for the purpose of illustration are shown preferred embodiments of our invention, attention is directed first to Figures 1 and 3 to 6 inclusive, wherein the numeral 20 designates an elongated straight cylindrical rod or bar, which may be flattened and beveled at one end to form a screw driver blade 21 and which may have a squared extension or end 22. Mounted upon rod 20 near and inwardly of the squared extension 22 is a straight intermediate cylindrical sleeve 23 having a bore 24, somewhat larger than the diameter of the rod 20 and slidably receiving the rod therein. The rod 20 extends for a substantial distance beyond the end of the sleeve 23 remote from the extension 22. Near the longitudinal center of the intermediate sleeve 23, it is provided in its side with a transverse slot 25, adjacent to and communicating with a diametrical groove or notch 26 formed in the rod 20 and extending transversely therethrough and having a flat bottom 27, passing through the center of the rod as shown. Mounted within the slot 25 and notch 26 is a substantially semi-circular plate or "Woodruff" key 28, which serves to connect the rod 20 and sleeve 23 and to prevent relative longitudinal movement of these elements. The bottom 29 of the slot 25 engages the straight bottom edge 30 of the "Woodruff" key 28 to maintain it spaced slightly from the bottom 27 of the notch 26, and the key 28 is shiftable horizontally within the slot 25 and notch 26.

35 An outer thin cylindrical tubular sleeve or handle 31 is provided, and freeable rotatably mounted upon the intermediate sleeve 23. The open end 32 of the handle 31 terminates near and inwardly of a bevel or chamfer 33 formed upon the adjacent end of the sleeve 23, and the outer closed end 34 of the handle is spaced longitudinally outwardly of the opposite flat end 35 of the sleeve 23. Near and inwardly of the end 35, the sleeve 23 has an annular groove 36 formed in its periphery, and a pin or screw 37, fixedly secured to the handle 31 projects into the groove 36 for slidably connecting the handle with the sleeve 23 and for preventing relative axial movement of these elements.

50 Near and inwardly of the end 32, the intermediate sleeve 23 has a small radial opening 38, a radially inwardly spring pressed ball or detent 39, which engages either of two flat faces 40 and 41, formed upon the rod 20, adjacent to the opening 38 and arranged at an acute angle and converging radially, Figure 3. The flat faces 40 and

41 constitute a pointed cam, Figure 3, for tripping engagement over the spring pressed ball 39 to position the rod 20 in either of two adjusted positions with respect to the intermediate sleeve 23. The outer circularly curved face 42 of the "Woodruff" key 28 is adapted to contact and to be wedged against the inner face or bore 43 of the handle 31.

We provide means to positively lock the handle 31 to the rod 20 so that they may be rotated upon their longitudinal axes as a unit. Such means comprises a narrow rectangular longitudinal rod or plate 44, longitudinally slidably mounted in an internal groove 45 formed in the bore 24 of the sleeve 23 and extending longitudinally throughout the entire length of the sleeve 23. The rod 44 extends longitudinally beyond both ends of the sleeve 23 for short distances and beyond the end 35 it is rigidly secured to a star-shaped or toothed plate 46 having a square opening or bore 47 slidably receiving the squared extension 22. The closed end 34 of the handle 31 has a star-shaped or toothed recess 48, for slidably receiving therein in the toothed plate 46. The remote end 49 of the rod 44 serves as a handle for shifting the rod longitudinally in either direction. Near and opposite the opening 38, the intermediate sleeve 23 has a small radial opening 50, housing a radially inwardly biased spring pressed ball 51 which engages small longitudinally spaced projections 52 formed upon the outer face of the rod 44 and shiftable longitudinally within a deeper end portion 53 of the longitudinal groove 45.

In operation, the rod 20 may be conveniently positively locked to the handle 31 by shifting the rod 44 longitudinally inwardly, to engage the toothed plate 46 in the tooth recess 48. When the rod 44 is shifted outwardly to its position of Figure 1, relative rotation between the rod 20 and handle 31 is possible.

With the spring pressed ball 39 engaging one of the flat faces 40, Figure 3, the force of the spring behind the ball will cause the rod 20 to be turned slightly upon its longitudinal axis, and one edge of the bottom 27 of notch 26 will engage the bottom 30 of the "Woodruff" key 28 and force the key radially outwardly into tight wedging and clamping engagement with the bore 43 of the handle 31. This in turn forces the intermediate sleeve 23 tightly against the bore 43 of the handle. When the handle 31 is now turned in one direction the "Woodruff" key will be more tightly wedged or bound, and the entire mechanism including the handle, intermediate sleeve 23, and rod 20 will rotate as a unit. When the handle 31 is rotated in the opposite direction, it will freely slip over the "Woodruff" key and sleeve 23 to produce the ratchet action. This ratchet action will be completely smooth and noiseless, and the reversal can be accomplished with ease, regardless of how much force has been exerted for turning up a screw or the like. The noisy clicking of most ratchet tools is absent. To reverse the direction of the ratchet mechanism, the thumb is held against the chamfer 33, which may be knurled, while the rod 20 is turned slightly until the ball 39 engages the opposite flat face 41. This will raise or force radially outwardly the opposite end of the "Woodruff" key 28, since it will be contacted by the opposite edge of the bottom 27. If the handle 31 is now turned in a direction opposite to that previously described, all of the elements will rotate as a unit, and the same ratchet motion will be produced, only in the opposite direction.

Attention is directed next to Figures 2 and 12, wherein a modified form of the invention is illustrated, and wherein the numeral 54 designates a rod, similar to the rod 20 and having one end squared as shown as 55 for connection with the socket of a wrench or the like. This end may of course be flattened to produce a screw driver blade like the blade 21, if desired. The rod 54 has angularly arranged flat faces 56 which are identical with the flat faces 40 and 41, and the rod is connected with an intermediate cylindrical sleeve 57 by a "Woodruff" key 58, in the same manner that the sleeve 23 and rod 20 are connected by the key 28. The intermediate sleeve 57 has a bore 59 terminating inwardly of a closed end 60, and this bore receives in its bottom a ball bearing 61 which engages the inner flat end 62 of the rod 54 to reduce friction between the rod and the intermediate sleeve 57. The sleeve 57 has its opposite end chamfered, as at 63 in the identical manner in which the sleeve 23 is chamfered at 33. A handle 64, corresponding to the handle 31 is freely rotatably mounted upon the sleeve 57 and carries a pin or a screw 65 which engages within an annular groove 66 formed in the side of the sleeve 67. This arrangement is identical to the corresponding arrangement shown and described in connection with the first form of the invention.

The handle 64 has a closed end 67, having a plurality of circumferentially spaced recesses 68 formed in its inner face, adjacent to the end 60. A longitudinally shiftable locking rod 69 is slidably mounted within a longitudinal bore 70 extending entirely through the sleeve 57, radially outwardly of the bore 59. The rod 69 has a handle extension 71 and is adapted to be reciprocated for engagement within the openings or recesses 68, and for disengagement from these recesses. Near and inwardly of the chamfer 63, the sleeve 57 has a surrounding eccentric groove 72, receiving a C-shaped spring 73 which is biased close for tight clamping engagement within longitudinally spaced notches 74 formed in and spaced longitudinally of the rod 69. One end 75 of the spring 73 is anchored within a small radial recess 76 formed in the bottom of the eccentric groove 72, Figure 12. The action of the spring 73 is such that the rod 69 may be shifted longitudinally into and out of any one of the openings 68 and the spring will engage alternately within the inner and outer notches 75 when the rod is so shifted. The rod 69 thus serves to positively lock the handle 64 and intermediate sleeve 57 together for rotation as a unit, and to release these parts for free relative rotation.

Formed in the outer end of the sleeve 57, adjacent to its chamfer 63 and arranged radially between the bore 59 and chamfer is a longitudinal opening or bore 91, within which is mounted for reciprocation an outwardly biased spring pressed cylindrical plunger or pin 92, having formed in its side a shallow recess 77, leading into a deeper recess or ball seat 78. The sleeve 57 has a radial bore or opening 79 formed in its side adjacent to the flat faces 56, and intersecting the bore 91. A ball detent 80 is mounted within the bore 79 upon the inner side of the plunger 92 and between this plunger and the rod 54. This ball detent 80 is normally seated within the shallow groove or recess 77, which maintains the ball in contact with one of the flat faces 56. When the plunger 92 is shifted inwardly against the spring, the ball 80

may move radially outwardly into the deeper seat 78 so that it may pass from one flat face 56 to the opposite flat face 56 in a similar manner to the manner in which the ball 39 passes from the flat face 40 to the flat face 41.

In view of the description, it is believed that the use and operation of the form of the invention illustrated by Figures 2 and 12 should be obvious, in the light of the description of the use and operation of the first form of the invention. Attention is directed next to Figures 7, 9, 10, 12 and 13, wherein a further modification of the invention is illustrated, and wherein the numeral 81 designates a rod which may be substantially identical to the rod 54 except that a recess or notch 82 is provided which is substantially longer than the recess 27. An intermediate sleeve 83 is mounted within a handle 84 and upon the rod 81, and this sleeve and handle are identical with the sleeve 57 and handle 64 in all respects, except that the sleeve 83 is provided in its side with a long radial opening or passage 84', for registration with the recess 82. Instead of the "Woodruff" key 58, a cylindrical roller or key 85 is introduced into the opening 84' and engages within the recesses 82, Figures 7 and 10. The roller 85 is shiftable radially within the opening 84', and there is some radial clearance between the bore of the handle 84 and the bottom of the recess 82. All other elements and their operation are identical with those shown and described in the first and second forms of the invention, and an additional detailed description is thought to be unnecessary. The roller 85 serves the same purpose as the "Woodruff" keys 28 and 58, and will function satisfactorily to produce the ratchet action in either direction, depending upon which flat face 40 or 41 the ball detent 39 is engaging.

Attention is directed next to Figures 8 and 11, wherein a still further modification of our invention is illustrated. In these figures, the numeral 86 designates a rod which may be identical with the rod 54. The numerals 87 and 88 designate an intermediate sleeve and handle respectively, identical in all respects with the corresponding parts shown and described in connection with the other forms of the invention, except that the sleeve 87 has formed in its side adjacent to the recess 27 a relatively short radial opening or passage 89 for receiving a steel ball 90, disposed therein and within the recess 27, between the bottom thereof and the bore of the handle 88. This ball 90 will function in a manner similar to the functioning of the roller 85 and "Woodruff" keys 28 and 58, and it has been found that any of these elements is satisfactory to produce the previously described ratchet action in either direction. In view of the foregoing descriptions, it is thought that a further detailed description is unnecessary, and that the use and operation of the mechanism in Figures 8 and 11 is obvious.

It is to be understood that the forms of our invention, herewith shown and described are to be taken as preferred examples of the same, and that various changes in shape, size and arrangement of parts may be resorted to, without departing from the spirit of our invention, or the scope of the subjoined claims.

Having thus described our invention, what we claim is:

1. Ratchet mechanism, comprising a rod provided in its side with a recess and having opposed converging flat faces, an intermediate sleeve

mounted upon the rod for limited rotation and having a first side opening adjacent to said recess and a second side opening adjacent to said flat faces, a ball mounted within said second side opening for engagement alternately with the flat faces, means carried by the intermediate sleeve and engaging the ball for releasably holding the ball in contact with either of said flat faces, an outer handle sleeve rotatably mounted upon the intermediate sleeve, a key element mounted within the recess of the rod and first side opening of the intermediate sleeve and adapted to shift radially into engagement with the side of the outer handle sleeve when the rod is turned, the key element holding the rod and intermediate sleeve against relative longitudinal movement, means connecting the intermediate sleeve and outer handle sleeve and preventing relative longitudinal movement thereof, and adjustable locking means carried by the intermediate sleeve and shiftable longitudinally of the intermediate sleeve into and out of locking engagement with the outer handle sleeve.

2. Ratchet mechanism, comprising a rod provided in its side with a recess and having opposed converging flat faces, an intermediate sleeve mounted upon the rod for limited rotation and having a first side opening adjacent to the recess and a second side opening adjacent to the flat faces, a ball mounted within the second side opening for engagement alternately with the flat faces, means carried by the intermediate sleeve and engaging the ball to releasably hold it in contact with either of the flat faces, an outer handle sleeve rotatably mounted upon the intermediate sleeve, a key element mounted within the recess of the rod and first side opening of the intermediate sleeve and adapted to shift radially into engagement with the outer handle sleeve when the rod is turned, the key element holding the rod and intermediate sleeve against relative longitudinal movement, means connecting the intermediate sleeve and outer handle sleeve and preventing their relative longitudinal movement, a longitudinally shiftable locking rod carried by the intermediate sleeve for locking engagement with the outer handle sleeve, and spring means mounted upon the intermediate sleeve and engaging the locking rod to releasably position it in locking and unlocking positions relative to the outer handle sleeve.

3. Ratchet mechanism, comprising a rod provided in its side with a recess and having a flat face, an intermediate sleeve slidably mounted upon the rod and having a side opening adjacent to said recess and a second side opening adjacent to the flat face, a spring pressed ball mounted within the second side opening and engaging the flat face, an outer sleeve rotatably mounted upon the intermediate sleeve, a "Woodruff" key mounted within the recess of the rod and first named side opening and engaging the inner surface of the outer sleeve, the key preventing relative longitudinal movement between the rod and intermediate sleeve, means to prevent relative longitudinal movement of the intermediate sleeve and outer sleeve, and a longitudinally shiftable locking rod carried by the intermediate sleeve and shiftable into and out of locking engagement with the outer sleeve.

4. Ratchet mechanism, comprising a rod provided in its side with a recess and having a flat face, an intermediate sleeve slidably mounted upon the rod and having a side opening adjacent to said recess and a second side opening adjacent

to the flat face, a spring pressed ball mounted within the second side opening and engaging the flat face, an outer sleeve rotatably mounted upon the intermediate sleeve, a "Woodruff" key mounted within the recess of the rod and first named side opening and engaging the inner face of the outer sleeve, the key preventing relative longitudinal movement of the rod and intermediate sleeve, the intermediate sleeve having an external annular groove, an inwardly projecting element secured to the outer sleeve and engaging within the groove to prevent relative longitudinal movement of the intermediate sleeve and outer sleeve, one end of the outer sleeve being spaced longitudinally from one end of the intermediate sleeve and having a toothed recess, a toothed plate slidably mounted upon the rod between said ends of the outer and intermediate sleeves, a longitudinally shiftable locking rod carried by the intermediate sleeve and secured to the tooth plate for shifting the same into and out of the toothed recess, and spring means for releasably holding the locking rod in locking and unlocking positions.

5. Ratchet mechanism, comprising a rod provided in its side with a recess and having a flat face, an intermediate sleeve mounted upon the rod and having a side opening adjacent to the recess and a second side opening adjacent to the flat face, a spring pressed ball mounted within the second side opening and engaging the flat face, an outer sleeve rotatably mounted upon the intermediate sleeve and held against longitudinal movement with respect to the intermediate sleeve, a cylindrical roller mounted within the recess of the rod and first named side opening and engaging the inner face of the outer sleeve, the roller preventing relative longitudinal movement between the rod and intermediate sleeve, and a longitudinally shiftable locking rod carried by the intermediate sleeve and shiftable into and out of locking engagement with the outer sleeve and serving to prevent relative rotation between the intermediate sleeve and outer sleeve.

6. Ratchet mechanism, comprising a rod provided in its side with a recess and having a flat face, an intermediate sleeve mounted upon the rod and having a side opening adjacent to the

5 recess and a second side opening adjacent to the flat face, a spring pressed ball mounted within the second side opening and engaging the flat face, an outer sleeve rotatably mounted upon the intermediate sleeve and held against longitudinal movement with respect to the intermediate sleeve, a ball mounted within the recess of the rod and first named side opening and engaging the inner face of the outer sleeve, the ball preventing relative longitudinal movement between the rod and intermediate sleeve, and a longitudinally shifting locking rod carried by the intermediate sleeve and movable into and out of locking engagement with the outer sleeve to prevent relative rotation between the outer and intermediate sleeves.

7. Ratchet mechanism comprising a rod provided in its side with a recess and having opposed converging flat faces, an intermediate sleeve mounted upon the rod for limited rotation and having a first side opening adjacent to said recess and a second side opening adjacent to said flat faces, a means mounted within said second side opening and engageable alternately with the flat faces, spring means operatively connected to said means for urging the latter into contact with either of said flat faces, an outer handle sleeve rotatably mounted upon the intermediate sleeve, a key element mounted within the recess of the rod and first side opening of the intermediate sleeve and adapted to shift radially into engagement with the side of the outer handle sleeve when the rod is turned, the key element holding the rod and intermediate sleeve against relative longitudinal movement, and means connecting the intermediate sleeve and outer handle sleeve and preventing relative longitudinal movement thereof.
